UNITED STATES PATENT OFFICE

JOSEF B. DECKER, OF ELKTON, MARYLAND

FIRECRACKER

Application filed October 27, 1928. Serial No. 315,460.

This invention relates to pyrotechnic devices and more particularly to a container for explosive compounds for use in such devices and to a method of making the same.

5 It is a general object of the present invention to provide a novel and improved container for explosive compounds for pyrotechnic devices and a novel method of forming the same.

10 Particularly, it is an object of the invention to provide a novel method of folding and forming a sheet of suitable material about a charge of explosive compound to form a substantially cylindrical packet containing

15 said compound and being of sufficient strength to provide such resistance as to cause a loud report when the compound is ignited.

A feature of the invention consists in the provision of an explosive container formed 20 of alternately interleaved convolutions of a fibrous material containing between alternate convolutions a charge of explosive material.

A further feature of the invention comprises a container for explosive material consisting of a pocket, having a short side and a long side, rolled in such a manner as to provide a cylinder with the long side of the pocket forming an end thereof which can be tied about a fuse extending into the pocket.

30 A still further feature of the invention consists in the provision of an explosive container formed for the most part of a cylinder rolled from a double thickness of fibrous material but being completed by a single 35 thickness of material adhesively secured around the outer surface thereof and integral with the main portion of the material.

The present invention is illustrated by way of example only in connection with the explosive container for a fire cracker and will be readily understood by reference to the accompanying drawing and following specification. It is to be understood that the form shown is exemplary only and that such 45 changes may be made therein as fall within the scope of the attached claims.

In said drawing:

Figure 1 is a plan view of a sheet of material with a charge of explosive and fuse resting thereon;

Figure 2 illustrates the first step in forming the explosive container;

Figure 3 illustrates the next step;

Figure 4 illustrates the rolled-up cylinder with the tab having adhesive applied thereto;

Figure 5 is a perspective showing the completed explosive container; and

Figure 6 is a longitudinal section through a fire cracker provided with an explosive container constructed according to the present invention.

In the manufacture of various pyrotechnics and particularly certain types of fire crackers or salutes, it has been found desirable to place the explosive in a container or bag, usually formed of paper or similar fibrous material, into a cylinder, and then to slip this cylinder inside of a rigid tube to provide added resistance against disruption at the time of explosion to increase the noise. A fire cracker constructed in accordance with this general custom is shown in Fig. 6, where the tube 10 is usually formed of a series of convolutions of paper with adhesive between the convolutions. Within the tube is a bag or container 11 holding explosive material and having projecting from one end a fuse 20 which sticks out beyond the end of the tube 10. The present invention provides a novel explosive container and method of making the same.

Referring to Fig. 1, it will be seen that the main portion of the container 11 is a sheet of suitable fibrous material, such as kraft paper, which is quite flexible and yet strong. In this figure, the paper is indicated by the reference character 13 and is of generally rectangular shape with the reentrant corner 14. The dotted lines on the paper indicate areas into which it can be considered to be divided for the purposes of the present description. On this basis the sheet may be considered to comprise a main rectangle defined by the lines 15 and 16 and the two outer edges of the sheet and having a side tab 17 of rectangular form and an end tab 18 of similar shape.

A suitable charge of explosive material 24, such as, for instance, a mixture of potassium perchlorate, sulphur and aluminium powder, is placed as indicated on a section of the area 19. Then a fuse 20 of any well-known type is

arranged with one end buried in the pile of explosive material, which is granular or powdered, and its other end extending beyond the edge 21 of the sheet.

5 The side tab 17 is next folded up to the position indicated in Fig. 2, where it covers substantially all of the explosive and, in effect, forms with the main rectangle an elongated pocket closed at the bottom and having a
10 short side formed by the tab and a long side formed by the main rectangle. As the next operation, the folded or doubled portion to the right of the fuse and explosive is turned over the explosive along the line indicated at
15 22 in Fig. 1. Now there will be a long portion of the pocket wall on each side of the explosive, and the fuse will be confined.

The next step consists in rolling the sheet and its contained powder in the direction of
20 the arrow in Fig. 3, forming it into as tight a cylinder as possible. During this operation, it will be evident that a certain amount of explosive will be forced longitudinally along the pocket and beneath the folded portion indicated by the reference character 23 in Fig. 3, so that when the container assumes the form indicated in Fig. 4, it will be seen to consist of an elongated pocket having explosive distributed throughout a considerable portion of its length with the pocket rolled into a cylinder of several convolutions. Another way of looking at it is that it comprises alternate interleaved convolutions of two lengths, i. e., the tab 17 and the main rectangle with an explosive between adjacent convolutions.

When the condition shown in Fig. 4 has been reached, the tab 18 of a single thickness of paper alone remains, and this is either at
40 the time or previously coated with a suitable adhesive. Continued rolling causes this tab to adhesively secure itself about the cylinder and hold the same in its rolled-up position against the unrolling tendency due to the resilience of the paper.

The next operation consists in wrapping and tying a thread or a small string 25 about the end of the cylinder close to the fuse. This will tie down and close the end of the pocket
50 into a neck to engage tightly about the fuse and prevent the escape of gases around the fuse during explosion and at the same time serve to retain the fuse in position. It will be noted that this neck portion which is
55 crimped in about the fuse is formed only by that part of the paper which extends beyond the turned-up edge 24 of the tab 17, and hence has only about one-half as much paper in it as the remaining portion of the cylinder, so
60 that it can be readily compressed by the string 25. The finished diameter of the cylinder is such that it can readily be placed within a tube such as 10 and either retained in there by its friction or secured by an application of suitable adhesive.

The resulting container for explosive material produced by the method just described is very simple to make and produces an extremely compact package of an explosive material which is sufficiently strong to resist the expanding of the gases upon explosion so as to cause a loud report. The feature of providing two tabs of the rectangle, one to be folded over the explosive and one to be provided with adhesive, are considered to be important features of the invention. Furthermore, the feature of having a reduced number of layers of paper at the end of the cylinder where it is secured about the fuse is of extreme importance, since it simplifies the operation of tying and insures a tighter joint between the fuse and the walls of the envelope or bag for the explosive.

Having thus described the invention, what is claimed as new and desired to be secured by Letters Patent is:

1. The method of making a fire-cracker comprising forming a sheet of fibrous material of rectangular form with a reentrant corner, placing explosive on a portion of said sheet, folding one of the tabs formed by said cut-out corner over said explosive, folding a portion of the doubled sheet over said explosive and then rolling the sheet and explosive into a cylinder.

2. The method of making a fire-cracker comprising forming a sheet of fibrous material of rectangular form with a reentrant corner, placing explosive on a portion of said sheet, folding one of the tabs formed by said cut-out corner over said explosive, folding a portion of the doubled sheet over said explosive, rolling the folded sheet into a cylinder, gumming the remaining tab and rolling it about said cylinder.

3. The method of making a fire-cracker comprising forming a sheet of fibrous material into a rectangle having a side and an end tab each smaller than the rectangle, placing a charge of explosive material on a portion of said rectangle, folding said side tab over said explosive, rolling said doubled portion of material and explosive and adhesively securing said end tab thereabout.

4. A fire-cracker formed of interleaved, alternate convolutions of fibrous material secured together at one edge to form a spiral pocket, explosive in said pocket, a fuse entering said pocket and means to secure the ends of one set of said convolutions about said fuse.

5. A fire-cracker formed of interleaved alternate sets of convolutions of fibrous material secured together at one edge to form a spiral pocket, means closing one end of said pocket, explosive in said pocket, a fuse entering said pocket, one edge of said pocket being beyond the other and means securing the additional material about said fuse.

6. A fire-cracker formed of interleaved, alternate sets of convolutions of fibrous material secured together at one edge to form a spiral pocket, means closing one end of said pocket, explosive in said pocket, a fuse entering said pocket, and a group of adjacent convolutions adhesively secured around the interleaved convolutions.

In testimony whereof I hereunto affix my
10 signature.

JOSEF B. DECKER.
